George Page
Savers Patent

The schedule of marks on these letters patent and making part of the same, containing a description of the tools of the said George Page, himself of his improvement called the cutting and clearing chisel.

The improved chisel, which is called a cutting and clearing chisel is described as follows: - The lower or cutting edge of this chisel is otherwise perfectly resembles a common chisel, is made in the shape of a box, open at top and bottom with four sides, the angles being right angles, and the main body of the chisel constituting one side of the box. The box is on the bevelled side, of the main part of the chisel. The inner width of this box at the bottom part of it, measuring from the edge of the main part of the chisel to the opposite edge is, in all cases, about three sixteenths of an inch and should gradually increase to the top. Its dimension the other way or its longitudinal dimension is, according to the size, width of the chisel. Supposing the chisel to stand upright, the two edges are not horizontal, but that which is, the end of the main part of the chisel, is about one tenth of an inch lower than the opposite edge, and the two side edges have a regular slope so that from one of the before mentioned edges, to the other so that the first mentioned edge goes forward in cutting the wood, and the two side edges follow, and trim the sides of it. The height of the three short sides of the box should be from one half to three quarters of an inch. - The beveling larger on one end, that is, to say wider at the top than at the bottom. It holds the chip first and until it is driven up and out of the box by those cut afterwards. The edges of the sides of the box are well sharp. The main edge which goes forward in cutting and the two side edges are bevelled on the inside. The edges should be made of steel and the three cutting edges of very tempered. The cutting and clearing chisel is designed to be used principally in marking for making mortises, when the work is to be made in hard wood. one head should be used, the diameter of which must be the same as the width of the chisel, and this mortise is to be cut to the left upright as may be most convenient about one

1771

depth of an inch at a time the face of the chisel going forward until it comes to the head of the mortise. The chisel is then turned and the mortise is cut in the same manner to the other head of it. When the mortise is to be made in soft wood, no hole need be bored, but if the mortise is to be continued beyond one end of it, the mortise may be begun near one end of it and the cuts shallow at first, may be made deeper and deeper until the desired depth is obtained and the chisel afterwards turned and the first end finished. This chisel may be used in turning the heads and corners of all mortises, however made.

Solemnly as my invention the addition of a fourth edge, or in other words, that side of the tool before described which is opposite to the main part of the chisel, and serves as a support to the side edges.
